UNITED STATES PATENT OFFICE.

FRANK LEVECK, OF PAWTUCKET, RHODE ISLAND.

COMBINED CIGAR BRANDING AND TRIMMING MACHINE.

SPECIFICATION forming part of Letters Patent No. 644,296, dated February 27, 1900.

Application filed December 6, 1899. Serial No. 739,453. (No model.)

To all whom it may concern:

Be it known that I, FRANK LEVECK, a citizen of the United States, residing at Pawtucket, in the county of Providence and State 5 of Rhode Island, have invented certain new and useful Improvements in a Combined Cigar Branding and Trimming Machine; and I do declare the following to be a full, clear, and exact description of the invention, such 10 as will enable others skilled in the art to which it appertains to make and use the same, reference being had to the accompanying drawings, and to the letters of reference marked thereon, which form a part of this specification.

15 My invention relates to improvements in a combined cigar branding and trimming machine; and the purpose of my invention is to provide a machine in which the cigar may be branded and securely held by one portion of the mechanism, while it is trimmed at the same time with another part of the mechanism, and in which the trimming device is insulated from the source of heat used to heat 20 the brand or stamp. I accomplish these objects by the mechanism shown in the accompanying drawings, in which—

Figure 1 is a side elevation of my machine; Fig. 2, a portion of the same, showing a cigar 25 as it is being branded. Fig. 3 is a vertical end view; Fig. 4, a sectional view through the fire-box and source of heat, and Fig. 5 a completed and stamped cigar.

The same letters refer to the same parts of 30 the mechanism throughout the various figures.

In Fig. 1, A is the framework of the machine, and B a hollow box (shown in section in Fig. 2) into which projects the tip of a gas-burner C. Securely fastened to the base of 35 A is the fixed tube c, acting as a guide to a cylindrical plunger b and permitting said plunger to slide easily up and down therein, the travel of b being determined by the slot b" and the screw b'.

40 s is a spiral spring keeping the plunger b at the top of its travel when not in use. Connected with b and fixed thereon at the top is the arm l, terminating in the holder d, piv-

oted on l by the pin e. Immediately over the 50 fire-box is the brand or stamp k, having thereon letters or characters projecting in relief k'.

Secured to the end of the frame A is the trimmer f i, the knife i being kept up when not in use by the spiral spring h, surrounding 55 the pin g, on which the knife i revolves.

The brand k is adjusted to various shapes of cigars by means of the screws v v.

In working my machine the cigar is placed 60 on the brand k, the holder d is brought down firmly upon the cigar by the plunger b and knob a, so that the heated brand k may stamp the required device plainly on the side of the cigar, and without releasing the cigar the operator brings down the trimmer i, cutting the 65 end of the cigar off square, as shown at i', Fig. 5. The pressure is then released on both a and f and the operation is completed.

In all combined trimming and branding machines now in use, so far as known to me, the 70 trimming-knife itself is connected in various ways with the body of the machine. As a result the knife becomes heated from the gas or other flame used to heat the brand and the temper is speedily destroyed and the handle of the trimmer frequently becomes too hot 75 for the hand of the operator. This is impossible in my device, as the flame of the burner C is first of all surrounded by the fire-box B, and, in addition, the trimming portion of the 80 machine is entirely insulated from the source of heat by the air-space o. The base A of the entire machine being constructed, preferably, of wood or some other non-conducting material, or, if made of metal, being insulated by 85 asbestos, will not conduct any appreciable amount of heat to the trimmer.

I am aware that prior to my invention branding-machines have been devised which incorporate a stationary brand and a reciprocating plunger and that combined branding and cutting machines have been used in which the brand was pressed upon the cigar and the end of the cigar trimmed by the same operation. I am not aware, however, that any combined branding and trimming machine has 90 been devised in which the flame is surrounded by a fire-box and in which the trimming ap-

paratus is insulated from the branding portion.

What I claim, therefore, and desire to secure by Letters Patent, is—

5 In a cigar trimming and branding machine the combination of a burner surrounded by a fire-box B, a vertical reciprocating plunger adapted to press the cigar against the brand; and a trimming device fixed to the base of the

machine and separated from the burner and fire-box by an air-space σ , all as described.

In testimony whereof I affix my signature in presence of two witnesses.

FRANK LEVECK.
